UNITED STATES PATENT OFFICE.

FRANK R. McGEE, OF STEUBENVILLE, OHIO.

DUST CATCHER.

Application filed April 6, 1921. Serial No. 458,988.

To all whom it may concern:

Be it known that I, FRANK R. McGEE, a citizen of the United States, and resident of Steubenville, in the county of Jefferson 5 and State of Ohio, have invented certain new and useful Improvements in Dust Catchers, of which the following is a specification.

My invention relates to cleaning gases, 10 and while not limited to such uses, more particularly relates to the removal of finely divided impurities, such as coke or flue dust, or similar impurities, from blast furnace gases, the gases evolved in the operation of 15 by-product coke ovens, and similar apparatus.

One object of my invention is to provide a novel apparatus adapted to separate the heavier particles of impurities by gravity 20 and to separate the finer particles by centrifugal and centripetal forces.

Another object of this invention is the provision of a gas cleaner having improved means for automatically separating the gases 25 from the impurities and for trapping and isolating the separated impurities.

A further object is to provide novel means for inducing a flow of low pressure gases through the impurity receiving chamber to 30 prevent back pressure therein.

A still further object of my invention is the provision of a gas cleaner having the novel constructions, arrangements and combination of parts shown in the drawings, and 35 to be described in detail hereinafter and particularly pointed out in the appended claims.

Referring now to the drawings forming part of this specification, Figure 1 is a sectional elevation showing gas cleaning apparatus embodying the novel features of 40 my invention.

Figure 2 is a side elevation of the lower portion of my cleaner taken at right angles 45 to the sectional elevation of Figure 1.

Figure 3 is a sectional plan taken on the line III—III of Figure 1.

In the accompanying drawings, the numeral 2 designates the cylindrical outer casing 50 of my cleaner which is enlarged adjacent its lower end forming an impurity receiving chamber 3 and provided with a frusto-conical bottom wall 4, having a centrally arranged discharge opening closed by 55 a bell 5 having a counterweighted operating control lever 6.

The portion of the casing 2 above the impurity receiving chamber 3 forms an uptake 7 for the gas to be cleaned, which enters the impurity receiving chamber 3 through down-comers 8 and 9 and discharges the heavier particles of impurities by gravity into the chamber 3 before it rises through the uptake 7.

A tubular separating chamber or member 10 is mounted within the uptake portion of the casing 2 and spaced from the walls thereof and has its upper end closed by a top 11. The upper end of the casing 2 is closed by a wall 12 secured to the member 10 and the 70 side walls of the casing 2.

The separating chamber 10 is provided adjacent its upper end with a plurality of tangential inlet vanes 13 adapted to cause the gases passing from the uptake 7 into the 75 separating chamber to take on a centrifugal whirling movement, to thereby centrifugally throw out the impurities in an annular layer while expanding the gases centripetally to form a central core of cleaned gases. 80

The lower end of the separating chamber 10 extends within a second impurity receiving chamber 14 having a frusto-conical bottom 85 15 opening into the lower portion of the bottom 4 of the impurity receiving chamber 3. The chamber 14 is of greater diameter than the separating chamber 10 and extends upwardly around the separating chamber 10 forming a pressure relief zone 16 from which gas is drawn to prevent back 90 pressure. The upper end of the impurity receiving chamber 14 is closed by a wall 17.

A clean gas outlet main 18 is arranged within the lower end of the separating chamber 10 and spaced from the side walls thereof of forming an annular trap space 19 adapted to trap the annular layer of impurities thrown from the stream of whirling gases within the separator and direct said impurities into the chamber 14. 100

The outlet main 18 is adapted to receive the central core of clean gases and conduct them to a point of use.

The main 18 is in the form of a Venturi tube, that is, it converges to the point 20 and then diverges again, in the shape of two truncated cones joined in their smallest diameters. The result obtained by the use of such an outlet main is that the pressure of gas at a point immediately beyond the smallest diameter of the main is less than at any other point while the gas has a higher ve- 105 110

lacity. The reasons for desiring this low pressure area will be clearly explained below.

The outlet main 18 also acts as a choker during a slip, as during a slip the gases entering the separating chamber 10 will have a higher velocity and the great centrifugal effect due to this increased velocity together with the novel construction of the outlet main 18 will cause considerable back pressure to be created adjacent to the inlet end of the outlet main. The back pressure created at this point serves as a choker on the furnace, and smooths out sudden puffs induced by a slip, and in this way provides a uniform flow of gases beyond the point 20 in the main 18.

An auxiliary cleaning device 21 is located to one side of the main gas cleaner and has an inlet conduit 22 communicating with the pressure relief zone 16 of the impurity receiving chamber 14. An outlet conduit 23 for the cleaned gases leads from the cleaning device 21 to the low pressure area of the outlet main 18, thereby establishing communication from the pressure relief zone 16 of the impurity receiving chamber 14 through the inlet conduit 22, auxiliary cleaner 21 and outlet conduit 23 to the outlet main 18. The gases which enter the impurity receiving chamber 14 with the impurities are low in pressure, while the stream of clean gases within the main 18 is of comparatively high pressure. Therefore to induce a flow of the pressure gases from the pressure relief zone 16 in the impurity receiving chamber 14 through the auxiliary cleaner 21, into the clean gas outlet main 18, it is necessary to produce an area of low pressure, that is, pressure lower than that within the pressure relief zone 16 plus the pressure loss due to the travel of the gases through the auxiliary cleaner 21. The novel construction of outlet main 18 shown and described produces the low pressure area desired and induces the flow of gases from the pressure relief zone 16 through the auxiliary cleaner 21 and into the outlet main 18.

The impurities cleaned from the gases within the auxiliary cleaner 21 fall by gravity through the conduit 25 which communicates with the impurity receiving chamber 3 of the main cleaning device.

A rotary grizzly or other type of mechanically operated screen 26 is arranged below the counterweighted bell 5 and is enclosed within a dust and gas tight casing 27 which opens at its lower end into a pug mill 28 which is also enclosed in a gas and dust proof casing 29. A discharge spout 30 leads from the casing 27, through which particles not passing through the screen 26 are discharged. The pug mill is adapted to mix the particles of impurities that pass through the screen 26 with water and to discharge the mixture into a car 31 or the like.

The impurities discharged through the opening controlled by the bell 5 fall upon the screen 26 and the coarser particles of impurities such as coke and the like are screened out of the mass and discharged 70 through the spout 30 while the finer particles or dust pass through the screen and fall into the pug mill 28 and are mixed with water and discharged into the car 31.

The counterweighted lever 6 controlling 75 the bell 5 is of sufficient weight to prevent the bell 5 from operating until a predetermined amount of impurities have been deposited within the chamber 3, thus a sufficient amount of impurities is maintained within 80 the chamber 3 to seal the bottom of the second impurity receiving chamber 14 and prevent the flow of unclean gases from the downcomers 8 and 9 up through the chamber 14 and into the clean gas outlet main 18. 85

A locking bar 35 is threaded into a stand 36 below the counterweighted control lever 6 and is adapted to be engaged over the lever 6, when the pug mill is inoperative to prevent the bell 5 from opening to discharge 90 any impurities into the mill.

While I have shown but one embodiment of my invention, it will be understood that various modifications may be made without departing from the scope of my invention as 95 defined in the appended claims.

I claim:—

1. A gas cleaner comprising an outer casing, the lower portion of which is enlarged to form an impurity receiving chamber and 100 the portion above said impurity receiving chamber forming an uptake for the gas to be cleaned, a vertical tubular separator member arranged centrally within said outer casing and provided with a plurality of 105 tangential inlet ports at its upper end adapted to impart a whirling motion to the gases entering said separator, a second impurity receiving chamber extending upwardly and around the lower end of said tubular separator, an outlet pipe of less diameter than 110 said separator member having its one end extending within said member so as to provide an annular trap space around its periphery for the escape of the impurities 115 separated from the gas within the separating chamber, and means for inducing a flow of gas through said second impurity receiving chamber.

2. In a gas cleaner, a separating chamber, means for imparting a centrifugal whirling movement to the gases entering said chamber, an impurity receiving chamber, a Venturi tube like clean gas outlet main 120 communicating with said separating chamber, said main having a high velocity and low pressure area along its length, an auxiliary cleaning device, a conduit communicating with said impurity receiving chamber and said auxiliary cleaning device, and a 125

130

conduit leading from said auxiliary cleaning device to the high velocity and low pressure area in said outlet main, whereby gas is induced to flow through said impurity receiving chamber and through said auxiliary cleaning device into said outlet main.

3. In a gas cleaner, a separating chamber, means for imparting a centrifugal whirling movement to the gases entering said chamber, an impurity receiving chamber, a Venturi tube like clean gas outlet main communicating with said separating chamber, said main having a high velocity and low pressure area along its length, and means communicating with said impurity receiving chamber and said high velocity and low pressure area in said outlet main to provide for a flow of gas from said chamber into said main.

20 4. A gas cleaner comprising, an outer casing, the lower portion of which is enlarged to form an impurity receiving chamber and the portion above said impurity receiving chamber forming an uptake for the gas to be cleaned, a vertical tubular separator member arranged centrally within said outer casing, said separator member being pro-

vided with a plurality of tangential inlet ports at its upper end adapted to impart a whirling motion to the gases entering said separator, a second impurity receiving chamber arranged centrally within said first named chamber and extending upwardly around the lower end of said tubular separator, a Venturi tube like outlet main having 35 its one end arranged within and spaced from said separating chamber and adapted to conduct the clean gases from said separating chamber, said tube by reason of its shape being provided with a high velocity and low 40 pressure area, an auxiliary cleaning device, a conduit leading from the upper portion of said second impurity receiving chamber to said auxiliary cleaner, and a conduit leading from said auxiliary cleaning device to 45 the high velocity and low pressure area in said outlet main, whereby a low pressure of gas is induced to flow through said impurity receiving chamber and through said auxiliary cleaning device into said outlet main. 50

In testimony whereof I have hereunto set my hand.

FRANK R. McGEE.
